Primary Examiner — Mary Ann Calabrese(74) *Attorney, Agent, or Firm* — Thomas|Horstemeyer, LLP**CLAIM**

The ornamental design for an armchair, as shown and described.

DESCRIPTION

1. Armchair

Reproduction 1.1 is a perspective view; reproduction 1.2 is a right side view; reproduction 1.3 is a left side view; reproduction 1.4 is a front view; reproduction 1.5 is a rear view; reproduction 1.6 is a top view; reproduction 1.7 is a bottom view.

The broken lines shown in the drawings of the armchair are for the purposes of illustrating the environment and form no part of the claimed design.
